UNITED STATES PATENT OFFICE.

JOHN THOMAS GRADON, OF OXFORD, ENGLAND.

SUSPENDER FOR TROUSERS.

SPECIFICATION forming part of Letters Patent No. 766,342, dated August 2, 1904.

Application filed December 7, 1903. Serial No. 184,167. (No model.)

To all whom it may concern:

Be it known that I, JOHN THOMAS GRADON, a subject of the King of Great Britain and Ireland, residing at 5 Keble road, Oxford, county 5 of Oxford, England, have invented certain new and useful Improvements in Suspenders for Pants, Trousers, and other Articles of Wearing-Apparel, of which the following is a specification.

10 The object of my invention is to provide an easily-adjustable contrivance for suspending or supporting pants, especially at the back, tennis, cricket, foot-ball, boating, and other trousers, and other articles of wearing-apparel.

15 Briefly described, the contrivance is a safety-pin tab and is best understood by reference to the accompanying drawings, in which—

Figures 1 and 2 show the contrivance for 20 use as a pants-supporter. Figs. 3 and 4 show same as used for supporting tennis and like trousers in lieu of shoulder-braces. Figs. 5 and 6 show the contrivance for use when an ordinary trousers-button is lost. Fig. 7 shows 25 the contrivance as used for supporting skirts. Figs. 8 and 9 illustrate modifications thereof, and Fig. 10 a still further modification.

According to my invention the back of a 30 safety-pin A is sewed into one end of a tab B, leaving the pointed part of the pin free for attachment to the top of a pair of pants, trousers, or a shirt, as the case may be. The other end of this tab B is provided with an opening, which may be either round *a* or slotted horizontally or vertically *b*—that is, a transverse or longitudinal buttonhole—according to use, and the edges of this hole or opening are either sewed or provided with a brass eyelet. Midway between the back of the safety-pin 35 A and this opening *a* in the tab B a button C is or may be sewed, Figs. 5 and 6. The tab itself may be of linen, soft leather, or other material, and it may conveniently be from one inch to two inches long and from half an inch 40 to one inch broad.

45 The contrivance is used as follows: In or-

der to support the pants at the back, Fig. 2, the safety-pin A, Fig. 1, is attached to the top of the pants and the end of the braces passed through the opening *a* in the tab B 50 and fastened to the button on the trousers, Fig. 2. In order to support tennis, cricket, and the like trousers, Fig. 4, the safety-pin A is attached to the shirt and the tab B, Fig. 3, fastened to the top trousers-button in front 55 by the buttonhole *b*, Figs. 3 and 4, or to the buttons at the sides or back.

Although I have thus far described my invention as applied to trousers and pants in the male sense of the words, yet it is easily 60 understood that I may apply the same device to supporting ladies' divided skirts, bloomers, combined cycling-skirts and knickers, and other garments by simply engaging the safety-pin A in the ladies' shirt-blouse and fastening 65 the tab to the button on the band of the skirt at the back. (See Fig. 7.) In this arrangement the tab and hole are made much shorter, inasmuch as they must be covered by the 70 waistband.

In Figs 8 and 9, which illustrate modifications of the skirt and like supporter, the tab or equivalent thereof is formed of metal either solid with the pin or adapted to be secured thereto. In Fig. 8 the tab B' is formed solid 75 with the pin A' by making in the back of the pin one or more bends or loops adapted to engage with a hook or hooks fastened on the skirt-band; but in Fig. 9 the tab B' is formed by coiling a wire round the back part 80 of the pin A', as shown, leaving one or more loops to engage with the aforesaid hooks on the skirt. In Fig. 10 the tab B'' is shown solid with the pin A'' and consists of a plate 85 having an opening *a* to engage with a button or hook on the skirt.

In order to support ordinary trousers in an emergency, as in the case of accident to or loss of the button, Fig. 6, the safety-pin A is attached to the top of the trousers and the 90 braces fastened to the auxiliary button C on the tab B, Figs. 5 and 6.

Having now described my invention, what I claim as new, and desire to secure by Letters Patent, is—

In a device of the character described, a pin, a supporting device carried thereby, said supporting device having a hole near its end and a button sewed to the supporting device.

In testimony whereof I have affixed my signature in presence of two witnesses.

JOHN THOMAS GRADON.
